UNITED STATES PATENT OFFICE

JOSEPH T. TWEEDALE, OF YARDVILLE, NEW JERSEY, ASSIGNOR TO HUSSONG DYEING MACHINE COMPANY, OF GROVEVILLE, NEW JERSEY, A CORPORATION OF NEW JERSEY

DYEING MACHINE

Application filed September 12, 1928. Serial No. 305,428.

This invention relates to dyeing apparatus and to new and useful improvements therein.

An object of the invention is to produce a new form of yarn stick holder.

5 Another object is to produce a new form of lock bar for yarn stick ends.

Another object is to produce a new form of division plate between the dyeing chamber and agitating chamber.

10 Still another object is to devise an improved means for preventing the yarn on the yarn sticks from entering the yarn stick holes.

Another object is to devise a new means for 15 supporting the propeller plate.

Another object is to devise a latching means for the lock bar for the ends of the yarn sticks.

20 Other objects will appear hereinafter.

In the drawings:

Fig. 1 is a top plan view of one form of the completed invention, parts being broken away and parts being shown in section;

25 Fig. 2 is a vertical, longitudinal section taken along the line 2—2 of Fig. 1;

Fig. 3 is a transverse vertical section taken along the line 3—3 of Fig. 2;

Fig. 4 is a transverse vertical section taken on line 4—4 of Fig. 2;

30 Fig. 5 is a detail, partly in elevation and partly in section, of the yarn stick holding and locking devices;

Fig. 6 is a side elevation of the locking bar and handles in position on the yarn rack;

35 Fig. 7 is a detail sectional view of the upper end of the division plate;

Fig. 8 is a detail sectional view of the lower end of the division plate;

40 Fig. 9 is a detailed illustration of the retaining member for preventing yarn getting in the yarn stick holes;

Fig. 10 is top plan view of a modified form of dyeing apparatus;

45 Fig. 11 is a side elevation of the lock bar for the device of Fig. 10;

Fig. 12 is end elevation of the device of Fig. 11;

50 Fig. 13 is a fragmentary transverse vertical section taken on line 13—13 of Fig. 11;

Fig. 14 is a detailed section of the locking

means for the lock-bar handles of Fig. 11;

Fig. 15 is a detailed section of the receiving means for the yarn stick, shown at the right hand side of Fig. 12 while

Fig. 16 is a detailed section of the receiving means for the yarn stick shown at the left hand side of Fig. 12.

Referring more particularly to Figs. 1-9, it will be seen that the dyeing apparatus comprises a base 1 having ends 2 and 3 and 60 sides 4 and 5. A movable top portion is shown at 6. If desired the top portion may be hinged, as at 6a.

As will be seen from Fig. 2, the dyeing apparatus is divided into an agitating chamber 65 7 and a dyeing chamber 8, by means of a division plate 9.

At the top and bottom of the effective portions of the dyeing chamber are perforated plates 10 and 11, respectively.

70 The top plate is supported by means which will be described later, while the bottom plate is in part supported by members 12 of channel or other suitable form.

Carried by transverse beams 13 and 14, 75 to which lifting eyes 15 and 16 may be attached, are longitudinally extending beams 17 and 18. Secured to beams 17 and 18 are hangers 19, 19 and 20, 20, from which is supported a yarn rack.

80 Formerly, when using wooden dyeing racks, the material on which the yarn sticks were supported was usually more than two inches thick thus furnishing sufficient bearing surface for the yarn sticks. When so constructed the yarn sticks seldom, if ever, dropped out.

85 Now however, it is found desirable to make yarn racks of metal, of thickness generally about one-eighth inch, which affords very little bearing surface for the yarn sticks.

When so constructed, a very slight swaying of the yarn rack will cause the sticks to slip out of the holes, especially as they are more slippery than the wooden sticks. To avoid

90 this, angles such as shown at 21 at the right hand side of Fig. 4 have been employed inside the yarn rack on both sides. However, this made it necessary to enlarge the stick holes to an objectionable degree in order to

enter the yarn-laden sticks into the rack. The yarn was found to be carried by the circulation of the dyeing liquid into the enlarged yarn-stick hole. It is therefore deemed essential, in order to procure the best results, that the sticks fit in the holes as snugly as possible.

As shown in Fig. 4, I accomplish this object by placing a Z-bar 22 on the outside of yarn rack 23. The yarn stick 24, loaded with yarn, is then inserted in the hole 25 in the yarn rack, where it rests on the angle 26, and is then slipped back past angle 21 until it rests upon and abuts the Z-bar 22. It will be noted that the Z-bar prevents the yarn sticks from dropping out or being drawn through the hole 27.

With this arrangement, it is necessary to lock the sticks into position on the opposite side of the yarn rack. In the present instance, the locking means takes the form of a locking plate 28. This plate is provided with preferably L-shaped slots 29, through which are inserted metal studs 30. The studs 30 may be inserted into the hangers 20 or into blocks attached to the yarn rack for that purpose.

By means of a sliding fit on the studs 30, the locking plate can be moved side-wise, and elevated or dropped, as the occasion requires.

To further secure the locking plate into position, a plurality of straps 31 of any suitable material are provided. As illustrated in Fig. 5, this strap comprises the U-shaped elements 32 and 33, secured together at their ends, and between which the locking plate 28 is vertically guided.

At various times while the skeins are under treatment, it is necessary to take samples, and in order to do so, the locking plate must be elevated to permit removal of a skein from one end of the yarn stick. When the yarn rack is lifted from boiling or hot solutions, the locking plate will be heated to about the temperature of the solution. Accordingly the bars 17 and 18 are interposed between the hangers 19 and 20 and the handles 15 and 16, and since these bars are of wood or other suitable insulators, they act as effective heat insulators.

Of course, it is understood that the dyeing apparatus is susceptible to use in a variety of sizes and shapes.

As will be noted in Figs. 4 and 5, the ends 55 of the yarn rack 25 are preferably bent outwardly to form flanges 34. These flanges are designed to prevent the flow of dyeing liquor between the inside of the vat and the outside of the yarn rack when the rack is seated in the vat. They are further designed to extend out just far enough to serve as a protection for the Z-bar on one side, and the angle, locking plate, and stud on the other side, in order that the parts referred to 60 will not catch on the top of the dyeing cham-

ber when the yarn rack is being entered therein.

The propeller chamber may be subdivided into one or more chambers 35 for the reception of propeller shafts and blades. These chambers are defined by a plate 36 having a plurality of openings (one for each propeller), straps or hangers 37, and walls 4, 5 and top portion 38. By supporting the propeller plate 36 from hangers the necessity of making holes through the dyeing chamber and lining is avoided.

It will be noted that the top 39 of division plate 9 is rolled back, in order that skeins will not become engaged with it when the yarn is lifted in or out of the machine. The bottom of the division plate 9 is flanged inwardly at 40 towards the dyeing chamber, the perforated plate 11 resting on the flange. The division plate is carried by any suitable means, such as angles (not shown) on the side walls.

Despite the use of my improved form of yarn rack, the holes for the yarn sticks are of necessity, still somewhat larger than the 20 yarn sticks. Because of this, when the dyeing liquor is circulated, a portion of the skeins adjacent the side of the yarn rack is carried by circulation into and through the holes in the side.

When the flow of dyeing liquor is reversed, it will be seen that the yarn stick is carried up or down with the liquor, and such yarn as has been carried into the yarn stick hole is likely to be pinched by the warn stick, and result in an undyed or untreated place; or with the rise and fall of the yarn stick and especially with fine counts of yarn, the yarn may be cut or weakened as a result of the weight and pressure of the stick against the thin metal yarn rack side.

To overcome this condition, metal wires 41 are arranged longitudinally along and secured to the inside of each of the two yarn rack sides. The wires are so located that they do not interfere with inserting or removing the yarn sticks from the rack. These wires are quite efficient in keeping the yarn out of the dye stick holes.

A metal lining 42 is provided throughout the apparatus, to prevent the liquor becoming clouded by reaction with the wood casing.

Referring more particularly to Figs. 10-16, it will be noticed that the outturned flanges 34 of yarn rack 27 are upturned as at 43, creating a round and smooth surface, and overcoming gouging or cutting as would be the case with a straight edge. In order to permit the liquor to drain out as the yarn rack is lifted from the dyeing chamber, properly spaced perforations 44 are provided in the flanges 34.

In this modification it has been deemed advisable to minimize the flow of liquor through the yarn stick holes, thus stopping 100

the liquor from carrying the yarn into the yarn stick holes and overcoming the pinching and undyed places where the yarn rack sides in the holes. It has further been found 5 advantageous to provide means which will more efficiently prevent cutting of the yarn by the upward and downward motion of the yarn sticks upon reversal of the flow of the liquor.

To accomplish these purposes, there has been substituted for the Z-bar of Fig. 4, a U- or other suitably shaped bar 45, extending substantially the full length of the yarn rack, and being provided on its under, parallel face with a plurality of properly spaced perforations 46, through which the liquor can drain upon removal of the yarn rack from the dyeing chamber. As will be noted from reference to Figs. 12, 13, 15 and 16, angles 47 have been placed on the interior of the yarn rack on both sides to keep the skeins away from the yarn stick holes, as a further means of overcoming the pinching, etc. In this manner the use of wires 41 is avoided.

In a further attempt to prevent scratching the lining of the apparatus members 48 are provided at both ends of one side of the yarn rack. These members have rounded edges and bottom, and are provided with grooves, 25 to guide the locking plate 49.

The locking plate 49 is elevated by handles 50, and when in lowered position rests on the Z-bar 51, which acts as both guide and support and which has perforations 52 by means 35 of which it can be quickly drained when lifted from the dyeing chamber.

The locking plate 49 differs from that shown in Fig. 6, in that it is movable only in a vertical path, by means of arms 52a, journaled in the top of the apparatus.

The top of the apparatus is provided adjacent the arms 52a with hollow lug portions 53. Through the aperture therein extends the plunger 54 having an exterior head 54. 45 Near the exterior end the aperture is interiorly threaded as at 55, which threads engage an exteriorly threaded hollow nut 56, which when in place retains a spring 57 in tension around plunger 54 by reason of its 50 coaction with an inner head 58 formed on the plunger. The head 58 engages an aperture 59 in arm 52, thus normally retaining the locking plate in raised position. When it 55 is desired to drop the plate 49 to rest on the Z-bar 51 the plunger 52 is retracted from engagement in the aperture 59, against the influence of spring 57, by means of outer head 53.

As will be readily apparent, this invention 60 is susceptible to numerous modifications, and it is intended that it be limited only by the scope of the appended claims.

I claim:

1. In a dyeing apparatus having a yarn 65 rack on which skeins of material to be dyed

are carried by means of yarn sticks, means cooperating with said rack to prevent the escape of yarn sticks therefrom, comprising a long plate having slots therein, through which studs protrude, said plate being guided 70 in vertical and lateral movements by said studs, and means for lifting said plate.

2. In a dyeing apparatus having a yarn rack holding yarn sticks by means of holes in the racks, a substantially Z-shaped bar 75 extending substantially the full length along the outer face of one side of the yarn rack, adjacent the holes therein, said Z-bar co-operating with means on the opposite side of the yarn rack to securely lock the yarn sticks 80 in position.

3. In a dyeing apparatus having a yarn rack holding yarn sticks by means of holes in the racks, a substantially Z-shaped bar extending substantially the full length along 85 the outer face of one side of the yarn rack, adjacent the holes therein, an angle bar adjacent to and underneath the holes and extending along the inner face of said yarn rack side, and an angle bar adjacent to and 90 underneath the holes and extending along the outer face of the other side of the yarn rack, said bars cooperating to form supports for the yarn sticks.

4. In a dyeing apparatus, a yarn rack, holding yarn sticks by means of holes in the rack, an angle bar extending substantially the full length of the inside of one side of said yarn rack, a substantially Z-shaped bar occupying a position similar to the angle bar 100 on the outside of said side, an angle bar on the outside of the other side of said rack, a movable locking plate on said last-mentioned side of the rack, and straps to guide said plate, the yarn sticks being entered in holes 105 on the side of the yarn rack, then moved over to abut the Z-bar and resting on the angle-bars, and being locked into position by said locking plate.

5. In a dyeing apparatus, a yarn rack holding yarn sticks by means of holes in the rack, a bar extending substantially the full length of the inside of one side of said yarn stick, an abutment bar occupying a position similar to the other bar on the outside 110 of one side of the rack, a bar on the outside of the other side, a movable locking means held in operative position on the last-mentioned side of said rack, and means to guide the plates, the yarn sticks being first entered 115 in holes on the side of the yarn stick having the locking means, than back through holes on the other side to abut the abutment bar, and to rest on the other bars; and being 120 locked in place by said locking means.

6. In a dyeing apparatus, a dyeing chamber, a substantially inverted U-shaped yarn rack substantially filling said yarn chamber, and having means for holding yarn sticks, 125 and a locking means mounted on said yarn 130

rack to close the ends of said yarn sticks after they are in position; said yarn rack terminating along its greater axis in outwardly turned flanges which prevent the holding means and locking means from catching on the chamber, upon insertion therein.

7. In a dyeing apparatus having a cover member and having a yarn rack in which there are holes for the reception of yarn sticks, means for closing the holes on one side of the rack, comprising a substantially vertically movable plate affixed to an arm extending through said cover member, and movable into position to close the holes on one side of the rack.

8. In a dyeing apparatus having a cover member and having a yarn rack in which there are holes for the reception of yarn sticks, means for closing the holes on one side of the rack, comprising a substantially vertically movable plate affixed to an arm extending through said cover member, and means for normally retaining the plate in a raised position, said means being operable to permit the plate to lower into position to close said holes on one side of the rack.

9. In a dyeing apparatus, a yarn rack having holes along its longitudinal side for the reception of yarn sticks, a substantially vertically movable locking plate for closing the holes along one side, a substantially Z-shaped bar along the outer face of said last-mentioned side for guiding and supporting said plate.

10. In a dyeing apparatus having a cover member and having a yarn rack in which there are holes for the reception of yarn sticks, means for closing the holes on one side of the rack, comprising a substantially vertically movable plate affixed to an arm extending through said cover member, and means for normally retaining the plate in a raised position, said means being operable to permit the plate to lower into position to close said holes on one side of the rack, said Z-bar having perforations along its central portion.

11. In a dyeing apparatus having a yarn rack in the sides of which there are openings for yarn sticks, end plates for the ends of one side of the rack, said plates being rounded at the bottom and edges, to avoid damage to the walls of the dyeing chamber.

12. In a dyeing apparatus having a yarn rack in the sides of which there are openings for yarn sticks, a movable locking plate for closing the openings along one side of the yarn rack, and end plates for the ends of the same side of the yarn rack, said end plates being rounded to avoid damage to the walls of the dyeing chamber, and being grooved to receive the edges of the locking plate and to act as guides therefor.

13. In a dyeing apparatus, a yarn rack having holes along its longitudinal sides for the

reception of yarn sticks, a substantially U-shaped bar along the outer face of one side of the rack, the yarn sticks resting in the U of the bar, and angle bars arranged along the inner face of each side of the rack for preventing the yarn from getting in the yarn stick holes.

14. In a dyeing apparatus, a yarn rack having holes along its longitudinal sides for the reception of yarn sticks, a substantially U-shaped bar positioned to receive in its channel the ends of yarn sticks projected through said holes, said bar having perforations along the lower parallel face.
